CLAIM

The ornamental design for a sound bar as shown and described.

DESCRIPTION

- 1.1: Perspective
1.2: Front
1.3: Back
1.4: Left
1.5: Top
1.6: Bottom
1.7: Enlarged

The right side view is omitted because it is a mirror image of the left side view; reproduction 1.7 is an enlarged view of the portion of reproduction 1.1 represented by the circle in dash-dot lines, curvy line and number 1.7; the broken lines indicate portions of the article that form no part of the claimed design.
